Patented Dec. 25, 1900.

C. BRANSGROVE.
CORD TENSION ALARM.
(Application filed Feb. 15, 1900.)

(No Model.)

Fig. 1.

UNITED STATES PATENT OFFICE.

CHARLES BRANGROVE, OF LULU, MICHIGAN.

CORD-TENSION ALARM.

SPECIFICATION forming part of Letters Patent No. 664,717, dated December 25, 1900.

Application filed February 15, 1900. Serial No. 5,335. (No model.)

To all whom it may concern:

Be it known that I, CHARLES BRANGROVE, a citizen of the United States, residing at Lulu, in the county of Monroe and State of Michigan, have invented a certain new and useful Cord-Tension Alarm, of which the following is a specification, reference being had therein to the accompanying drawings.

This invention relates to cord-tension alarms, and while especially designed for use on harvesters and grain-binders is also applicable as a burglar or fire alarm and may be employed in many places where it is desirable to throw in action a continuous alarm by which the fact that the parts have been disarranged is audibly indicated.

One object of the invention is to provide, in connection with a continuous alarm, a trip for throwing the alarm mechanism into action, which trip is held in engagement with the alarm mechanism and the latter inactive by the running cord or twine of a harvester, grain-binder, or other machine, the arrangement being such that when the cord breaks or the end of the cord is reached the alarm mechanism will be tripped and will operate continuously until it runs down or is stopped by the attendant. The operator having his attention called to the fact that the cord has broken or given out may at once repair the break in the cord or place a new ball of cord in the cord box or receptacle.

Other objects and advantages of the invention will appear in the course of the ensuing description.

The invention consists in certain novel features and details of construction and arrangement of parts, as hereinafter fully set forth, illustrated in the drawings, and incorporated in the claims.

In the accompanying drawings, Figure 1 is a perspective view showing the invention applied to an alarm-clock adapted to be fastened to a machine-frame. Fig. 2 is a detail section through the rear wall of the clock, showing the trip mechanism. Fig. 3 is a detail elevation of a modified form of trip, showing the friction-rollers in section. Fig. 4 is a detail view of another form of trip, showing a portion of the back of the clock-case in section.

Similar numerals of reference indicate corresponding parts in the several views.

The mechanism forming the subject-matter of this invention is of a very simple character and may be used in connection with any continuous alarm mechanism, with or without the ordinary time-clock mechanism.

In the drawings I have shown the common form of alarm-clock, (indicated at 1,) having the usual back 2 and held by a clamping rim or band 3.

4 designates the alarm-bell; 5, the hammer; 6, the hammer-arm, and 7 the pallet, connected to the hammer-arm and actuated by the wheel 8, which is revolved by the usual spring-actuated gearing. (Not shown.)

In order to attach the device as a whole to a convenient part of the frame of a harvester, binder, or other machine, a hollow base or pedestal 9 is adjustably connected with the clamping-band and for that purpose is provided with recesses 10, in which the extremities of the band 3 are received, one of such extremities being permanently but pivotally secured to the base by a screw 11 and the other by a thumb-screw 12, by turning which the rim or band 3 may be tightened or loosened for a purpose hereinafter described. Passing through the bottom of the base 9 is a bolt 13, by which the device may be securely fastened to the frame of any desired machine at any convenient point. The cord or twine (indicated at 14) passes through guide-eyes 15, which for convenience are illustrated in the form of holes in an annular flange or rim 16 on the clock-case, which is clamped within and held in place by the band 3 when the screw 12 is tightened. By loosening the screw 12 the case 1 and flange 16 may be partially turned to bring the holes 15 into line with the direction in which the cord 14 must run, such adjustment being illustrated by dotted lines in Fig. 1.

The trip mechanism comprises a spring-arm 17, secured at one end to a block 18 on the back of the case 1, so as to offset said arm from the back. The free end of the arm 17 carries a trip pin or finger 19, which works through an opening 20 in the back 2 and is held in the path of the hammer-arm 6 by the action of the cord on the spring-arm 17, thus holding the alarm mechanism inactive.

A bracket 21 is secured to the back 2 and is shaped to form a loop through which the arm 17 passes. A presser-foot 22 also passes

through the loop-bracket and is secured at one end to the arm 17, diverging toward its opposite end away from the arm 17 to leave a V-shaped space for the passage of the cord, which is thus frictionally grasped between said parts and held under the necessary tension. The guide-eyes 15 direct the cord and keep it in proper relation to the tripping device. An adjusting-screw 23 passes through bracket 21 and bears against the presser-foot 22 and serves as a means for regulating the pressure on the cord 14. Any bunch, knot, or other enlargement on the cord will, however, pass between the arm 17 and presser-foot 22 without breaking the cord. The cord may be taken from any suitable spool or bobbin under tension, if necessary, and as it passes through the guide-eyes 15 and between the arm 17 and presser-foot 22 holds the pin 19 in the path of the hammer-arm by overcoming the tension of the spring-arm 17. Should the cord, however, break or give out, the tension is relieved and the pin 19 is thrown outward by the arm 17, with the result that the continuous alarm mechanism is released and allowed to act.

The spring-arm and presser-foot may be constructed as shown in Fig. 3, in which 17' designates the arm, and 22' the presser-foot. In said figure both are shown as formed in one piece from a length of spring-wire and united by a spring-coil 24, the extremity of the arm being bent to form the trip-pin 19'. An annular enlargement 25 is provided on both the arm and presser-foot to form seats for a pair of antifriction-rollers 26, each having its upper end rounded or beveled, as shown, to facilitate the entrance of the cord between the rollers. One roller is also provided with an annular flange 27 at its lower end, which revolves beneath the other roller and prevents the cord from dropping below the rollers. The trip-arm may be connected to the alarm-case by a suitable bracket or in any convenient manner.

In Fig. 4 I have illustrated a trip of modified form. The trip is composed of a strip of spring metal, the spring-arm portion being shown at 17" and the extremity thereof being bent at an angle to form the trip-finger 19", which is pointed or made V-shaped and adapted to pass through an opening in the back of the clock-case in the manner above described. The lower portion of the trip is extended to form the presser-foot 22", and at an intermediate point the strip of metal is bent at substantially a right angle to form a transverse offset 29. This sets the spring-arm 17" away from the back 2 of the clock-case and also forms a bearing portion or rest 18", which lies against and is secured in any convenient manner to the back 2. The cord or twine passes between the spring-arm 17" and the presser-foot 22", the relation between the cord and the spring-arm and presser-foot being the same as that heretofore described.

From the foregoing description it will be

seen that the running cord, being under tension, acts to hold the trip in engagement with the alarm mechanism, the latter in turn being held inactive. As soon, however, as the cord breaks or runs out the trip-arm springs outward, drawing the trip-pin out of engagement with the hammer, which immediately begins to vibrate and impinge against the bell. The alarm rings continuously until it runs down, thus giving the attendant ample notice. 28 designates the key for winding up the continuous-alarm mechanism.

By pivotally connecting the clamping-band 80 with the base 9 the band, together with the clock-case held therein, may be adjusted to any desired angle with relation to the base. This enables the base to be attached to any convenient part of the machine-frame and the clock-case to be adjusted to a vertical position or to any angle which will allow the cord or twine 14 to pass in a straight line through the guide-eyes 15 and between the spring-arm and presser-foot. In some instances it may be necessary to provide an additional holder or hanger upon which to mount the alarm-case 1 or the base 9. I do not deem it necessary to illustrate such a hanger or holder, as its form will vary according to the machine to which the alarm is to be applied.

It will be obvious that changes may be made in the form, proportion, and minor details of construction without departing from the principle or sacrificing any of the advantages of the invention.

Having thus described the invention, what is claimed as new is—

1. The combination with continuous alarm mechanism, of a cord-controlled spring-arm, a trip-finger carried thereby and normally engaging the alarm mechanism, and a spring presser-foot on said arm between which and the arm a running cord is adapted to travel, substantially as and for the purpose described.

2. The combination with continuous alarm mechanism, of a cord-controlled spring-arm, a trip-finger carried thereby and normally engaging the alarm mechanism, a presser-foot and means for adjusting said presser-foot, substantially as and for the purpose described.

3. The combination with a suitable frame, of continuous alarm mechanism, an alarm-trip connected with the frame and controlled by a running cord, and a surrounding flange having opposite cord-guide openings, substantially as described.

4. The combination with an alarm-case and continuous alarm mechanism, of a cord-controlled spring-arm, a trip-finger carried thereby and normally engaging the alarm mechanism, an annular flange provided with cord-guide eyes at opposite sides, and an annular clamping-band in which the alarm-case is adjustably mounted, substantially as described.

5. The combination with an alarm-case and continuous alarm mechanism, of a band in which the case is rotatably adjustable, a cord-controlled spring-arm on the case, a trip-finger carried thereby and normally engaging the alarm mechanism, an annular flange on the case having cord-guide eyes, and means for clamping the case within the band, substantially as described.
- 10 6. The combination with continuous alarm mechanism, of a cord-controlled spring-arm,
- a trip-finger carried thereby and normally engaging the alarm mechanism, a presser-foot associated with the spring-arm, a bracket embracing the presser-foot and arm, and an adjusting-screw for adjusting the presser-foot, substantially as and for the purpose specified. 15

CHARLES BRANGROVE.
